[57] CLAIM

The ornamental design for a pair of hockey gloves, as shown and described.

DESCRIPTION

FIG. 1 is a front perspective view of a pair of hockey gloves showing my new design;

FIG. 2 is a rear elevational view thereof;

FIG. 3 is a top plan view of the left-handed glove;

FIG. 4 is a side elevational view thereof; and,

FIG. 5 is a bottom plan view thereof.

The undisclosed top, side and bottom views of the right-handed glove are a mirror image of FIGS. 3-5.

FIG. 3

FIG. 4

FIG. 5
